UNITED STATES PATENT OFFICE.

ISAAC M. SHARP, OF SAN FRANCISCO, CALIFORNIA.

ROTARY OIL BURNER.

Application filed April 16, 1919. Serial No. 290,895.

To all whom it may concern:

Be it known that I, ISAAC M. SHARP, a citizen of the United States, residing at the city and county of San Francisco and State of California, have invented new and useful Improvements in Rotary Oil Burners, of which the following is a specification.

This invention relates to an oil burner and particularly to a burner of the rotary type in which the oil is atomized and projected by means of centrifugal force.

One of the objects of the present invention is to provide a simple, substantial and cheaply manufactured oil burner of the rotary type, in which the oil is atomized and projected into the furnace by means of centrifugal force and in conjunction therewith to provide means for introducing a sufficient volume of air to support combustion.

Another object of the invention is to provide a novel form of atomizing head, means for delivering oil thereto, and means for obtaining an even distribution of the oil within the head before it is centrifugally discharged.

Another object of the invention is to provide means actuated by the incoming air for transmitting a rotary movement to the atomizing head and also to provide means for by-passing a sufficient volume of air through the atomizing head to prevent overheating of the same.

Further objects will hereinafter appear.

The invention consists of the parts and the construction, combination and arrangement of parts as hereinafter more fully described and claimed, having reference to the accompanying drawings, in which—

Fig. 1 is a longitudinal vertical section through the burner.

Fig. 2 is a cross-section on line 2—2, Fig. 1.

Referring to the drawings in detail, A indicates a cylindrical shaped casing, in one end of which is adjustably mounted a nozzle 2. This nozzle is threaded, as at 3, and turning movement of the nozzle will therefore permit longitudinal adjustment of the same with relation to the casing A and the atomizing head generally indicated at B, as will hereinafter be described. The opposite end of the casing is closed by means of a head member 4. This head member is in this instance provided for two purposes; first, that of supporting a bearing member 5; and secondly, that of supporting a connection 6 through which the oil to be burned

is admitted. The bearing member 5 is screwed into the head 4, as shown at 7. It may, however, be constructed integral with the casing, if desired. Formed in the outer end of the bearing member is a central chamber 8 and mounted within said chamber are a pair of ball bearings 9 in which is journaled a hollow shaft 10. Extending through the hollow shaft and supported by the bearing member is a stationary fuel delivering pipe 11. This pipe is threaded and is screwed into the bearing member, as at 12. The pipe communicates with the main delivery pipe 6, through means of a passage 13 formed in the bearing member and it serves the function of delivering the oil to the centrifugal atomizer B.

Suitably secured on the outer end of the hollow shaft is a head member 14 in which is formed a plurality of longitudinally disposed openings 15 and a plurality of radially disposed openings 16. Formed on the outer end of the head is a threaded extension 17 on which is secured a cap plate 18. Suitably secured exterior of the head member 14 is a cup-shaped atomizer 19, which is provided with an annular discharge lip 20. Formed between the head member by means of the threaded extension 17 and the cap plate 18 is a central chamber 21, into which the stationary oil delivering pipe 11 projects. Secured on the outer end of said pipe and within the chamber 21 are a pair of inverted cap members 22 and 23 and formed between said caps are a plurality of radially disposed openings 24 through which the oil is permitted to discharge. The cap 23 is larger in diameter than the inner cap 22, thus permitting the larger cap to partly enclose the inner cap. This is of considerable importance as the oil discharging through the radial openings 24 is thereby projecting downwardly into the bottom portion of the chamber 21 where it is permitted to discharge into the cup 19 through the radial openings 16. The caps 22 and 23 are of further importance as they prevent the oil discharging from striking the cap plate 18, which is often so hot during the operation of the burner that carbon might be formed.

By referring to Fig. 1, it will be seen that the outer end of the nozzle 2 is enlarged and flared, as at 25; also, that the discharge lip 20 of the atomizing cup, as turned at right angles, with relation to the longitudinal axis of the burner. This is of considerable

importance as it serves the function of a seat, with relation to which the discharge end 25 of the nozzle may be adjusted thereby controlling the volume of air discharging 5 between the atomizing cup and the nozzle.

Secured on the hollow shaft 10 or formed integral therewith, is a spiral-shaped vane 27 and forming a connection with one end of the casing *a* is a pipe 28 to which air is delivered by means of a blower or the like, not here shown. Air delivered in this manner has comparatively small pressure but it travels at great velocity. It will therefore 10 pass forwardly through the casing *a* and 15 through the discharge nozzle 2, being finally permitted to discharge through the annular opening 30 formed between the nozzle end 25 and the flange 20 of the atomizing cup, the air being here directed at right angles or 20 radially with relation to the cup. The air during its passage through the nozzle, engages the inclined face presented by the spiral-shaped vane 27. A rotary movement is in this manner imparted to the hollow 25 shaft and the centrifugal atomizer carried thereby and it will therefore atomize the oil delivered to the cup and also project the same. The number of revolutions obtained in this manner depends entirely upon the 30 velocity of the air and the incline or pitch of the spiral-shaped vane. It should, however, in all instances, approximate or preferably exceed 2000 revolutions per minute. In actual operation, it is found that the oil 35 delivered to the interior chamber 21 is discharged radially through the opening 16 into the bottom of the cup and here spreads out in a thin film over the interior wall of the cup and as this wall is inclined, it can 40 readily be seen that it will travel outwardly to the lip 20 and will then be projected as a thin annular sheet of vapor. This vapor mixes with the air discharging from the nozzle end 25 and a homogeneous combustible mixture is in this manner produced. 45 The flow of the air is in this instance divided as a considerable portion of the same is permitted to enter the cup through the longitudinal openings 15 formed in the 50 head. This air discharges through the annular opening 31 formed between the cap plate and the lip of the cup, thus discharging air also on the forward side of the projected oil vapor. In other words, air is delivered to both sides of the highly vaporized 55 oil and is therefore permitted to intimately mix with the same before combustion takes place. The flame produced in the present instance is circular in formation and may 60 be spread over a considerable area, the size of the flame being controlled to a great extent by the volume of oil delivered.

The air passing through the centrifugal atomizer promotes combustion, due to the 65 fact that it permits a more intimate mixture

of the air and oil and it also serves the function of preventing carbonization of the oil within the head as it retains the head sufficiently cool to prevent carbonization. The air passing through the nozzle 2 also 70 serves two functions; first, that of rotating the centrifugal atomizer; and secondly, that of supplying a sufficient quantity of air to support combustion. The air passing through the nozzle also serves another function, to-wit, that of maintaining the main bearing and the shaft supported by the same, cool, thus preventing overheating of the same and similarly, reducing lubricating 75 troubles. 80

A burner constructed, as here shown, is simple and substantial in construction and may be regularly applied to practically any type of furnace. It is, however, preferably designed to assume a vertical position when 85 in operation and may, therefore, be inserted directly through the bottom of a furnace, if desired. The longitudinal adjustment of the nozzle 2 with relation to the casing *A* and the discharge lip 20 of the atomizing cup is an important feature as it not only controls the volume of air discharging through the annular opening 30 but it also controls the volume of air passing through the atomizing cup, thus permitting an adjustment which will maintain an ideal temperature at this point and which will also, to a large extent, regulate the number of revolutions imparted to the atomizer. 90 95

While the burner here shown is more or 100 less specific in construction and design, I wish it understood that it may be varied within the limits of the scope of the claims; similarly, that the materials and finish of the several parts may be such as the experience and judgment of the manufacturer may dictate. 105

Having thus described my invention, what I claim and desire to secure by Letters Patent is—

1. In a burner of the character described a head member, a hollow shaft supporting the same, a centrifugal atomizing cup supported by the head member, a central cylindrical extension formed on the head member, 110 a cap supported thereby, said cap being spaced with relation to the centrifugal atomizing cup to form an annular discharge opening, an oil delivering pipe extending through the hollow shaft and the head member, 115 said pipe adapted to deliver oil to a chamber formed within the cylindrical extension on the head member, a plurality of radially disposed openings formed in the head member communicating with said central chamber and with the centrifugal atomizing cup to deliver oil thereto and a plurality of openings formed in the head member 120 for delivering air to the interior of the centrifugal atomizing cup. 125 130

2. In a burner of the character described
 a head member, a hollow shaft supporting
 the same, a centrifugal atomizing cup sup-
 ported by the head member, a central cylin-
 drical extension formed on the head member,
 a cap supported thereby, said cap being
 spaced with relation to the centrifugal atom-
 5 izing cup to form an annular discharge
 opening, an oil delivering pipe extending
 10 through the hollow shaft and the head mem-
 ber, said pipe adapted to deliver oil to a
 chamber formed within the cylindrical ex-
 tension on the head member, a plurality of
 15 radially disposed openings formed in the
 head member communicating with said cen-
 tral chamber and with the centrifugal atomiz-
 ing cup to deliver oil thereto, a plurality
 20 of openings formed in the head member for
 delivering air to the interior of the centrifu-
 gal atomizing cup, and a nozzle partially sur-
 rounding the centrifugal atomizer and the
 shaft, said nozzle being connected with a
 25 source of air supply.
3. In an oil burner of the character de-
 scribed, an outer casing and a nozzle in line
 therewith having a divergent discharge end,
 a hollow revoluble shaft, having a head
 member with a divergent cup concentric with
 30 the nozzle and a concave outer cap plate fac-
 ing the cup and spaced therefrom, both cap
 and cup having similar concentric peripher-
 ies, an interior concentric oil pipe with dis-
 charge openings within the head and a plu-
 rality of inverted mixing cups, radial pas-
 sages in the head through which oil is dis- 35
 charged between the outer cap and cup
 flanges, and longitudinal openings through
 the head, through which air under pressure
 from the rear of the nozzle is mixed with
 the oil. 40
4. In an oil burner of the character de-
 scribed an outer casing, a nozzle in line
 therewith having a divergent discharge end,
 a hollow rotatable shaft journaled in the
 casing having a head member with a diver- 45
 gent cup concentrically positioned with re-
 lation to the nozzle, a concave outer cap
 plate facing the cup and spaced therefrom
 to form an annular discharge opening, an
 interior concentric oil pipe passing through 50
 the hollow shaft and stationary with re-
 lation thereto, a plurality of radially disposed
 discharge openings formed in the end of said
 pipe and adapted to deliver oil to the cup,
 longitudinal openings formed in the cup 55
 through which air under pressure from the
 rear of the nozzle may enter, and means car-
 ried by the shaft and actuated by the air
 for imparting a rotary movement to the shaft
 and cup. 60
- In testimony whereof I have hereunto set
 my hand in the presence of two subscribing
 witnesses.
